UNITED STATES PATENT OFFICE.

CLARENCE A. HOY, OF BUFFALO, NEW YORK, ASSIGNOR TO PEERLESS HUSKER COMPANY, OF BUFFALO, NEW YORK, A COPARTNERSHIP.

CONVEYER.

Application filed March 8, 1921. Serial No. 450,766.

To all whom it may concern:

Be it known that I, CLARENCE A. HOY, a citizen of the United States, residing in Buffalo, in the county of Erie and State of New York, have invented new and useful Improvements in Conveyers, of which, the following is a specification.

This invention relates more particularly to a conveyer for use in connection with the ear feeding device of corn trimming and husking machines, but the same is also useful in other installations where similar conditions exist.

In that form of conveyers heretofore known in which endless belts were employed which were provided with carrying wings extending laterally from the belts for the purpose of engaging the articles to be propelled it frequently happened that the wings upon engaging such articles would be deflected rearwardly to such an extent that the articles would be liable to slip over the top of the wings or become otherwise displaced so that improper delivery or presentation of the articles would occur. This is particularly objectionable in the case of corn huskers in which it is necessary to move the ears of corn forward in proper relation to the trimming or cutting mechanism preparatory to delivering the same to the husking mechanism in order to ensure proper removal of the husks therefrom and obtain the maximum efficiency and capacity of the machine.

This difficulty has been due in the conveyers of corn trimming and husking machines, as heretofore constructed, by reason of the fact that the links of the chain belts employed for this purpose were comparatively short as this permitted the wings forming part of some of the links to tip backwardly under the pressure which was exerted against the ears of corn which were being propelled. It is undesirable to use longer links throughout the entire chain belt to overcome this difficulty, because this would involve unnecessary additional expense and also unduly increase the weight of the machine without corresponding gain by reason of the fact that in all standard makes of chain belting, the width of the links always increases in the same measure as the length of the same, in other words, comparatively short links are always narrow and when making links of greater

length the same will also be of corresponding greater width.

The present invention, therefore, contemplates the construction of a conveyer in which standard short and narrow links are employed in groups throughout the main portion of the chain belts of the conveyer which can be obtained at comparatively low cost from any manufacturer of standard chains, while only the particular links having wings or carrying members are made specially of greater length so as to avoid the objectionable tipping backwardly of the same when they engage the ears of corn and thus ensure proper feeding of the ears to the cutting or trimming and husking mechanisms.

The object of this invention, therefore, is the production of a conveyer of the chain belt type which is provided with carrying wings and which is so constructed that articles may be propelled by the same without liability of slipping over the wings and still enable the principal part of the conveyer to be constructed at low cost of standard materials.

In the accompanying drawings:

Figure 1 is a fragmentary top plan view of a corn husking machine having its trimming mechanism provided with my improved conveyer. Figure 2 is a longitudinal section of the same taken on line 2-2. Fig. 1. Figure 3 is a fragmentary vertical longitudinal section of a part of one of the chain belts of the conveyer provided with my improved form of carrying wing. Figure 4 is a horizontal section taken on line 4-4. Fig. 3. Figure 5 is a vertical transverse section taken on line 5-5, Fig. 3. Figures 6 and 7 are detached perspective views of a cross piece and side plate of one of the carrying sections.

Similar characters of reference refer to like parts throughout the several views.

Although this invention is capable of general use where similar conditions exist, the same is shown, for example, in the drawings, as embodied in a corn trimming and husking machine in which 20 represents the main frame of the machine, 21 the cutter past which the ears of corn are moved in a crosswise position for the purpose of trimming or cutting off the ends of the ears, 22 a pair of rotary husking rollers which re-

ceive the ears of corn after the ends of the same have been trimmed and which operates to remove the husks from the ears, and 23 an endless conveyer which operates to move the ears of corn lengthwise over the husking rollers and to discharge the husked ears therefrom.

In the present machine my improvement is embodied more particularly in the conveyer mechanism which operates to carry the ears of corn 42 from the front end of a feed table where they are fed into the machine past the end cutter trimmer and then to the husking rollers, and as shown in the drawings this conveyer mechanism is constructed as follows:

24 represents a plurality of receiving sprocket wheels which are arranged in a transverse row at the front or receiving end 20 of the feeding table 40 and mounted on a horizontal receiving shaft 27 which is journaled transversely in the front part of the main frame and 25 represents a plurality of delivery sprocket wheels which are arranged 25 in a transverse row at the rear end of the table and mounted upon a horizontal delivery shaft 28 which is journaled transversely in the rear part of the frame. Each of these sprocket wheels is provided with a row of sprocket teeth 26 which are spaced equidistant. Each of the receiving sprocket wheels is lengthwise in line with one of the delivery sprocket wheels and around this pair of sprocket wheels passes a conveyer belt which 35 moves with its upper operative stretch forwardly along the table. Each chain belt is constructed of a plurality of groups of comparatively short links and a plurality of comparatively long links, each of which is 40 arranged between two adjacent groups of short links and provided with a carrying wing which projects laterally therefrom and is adapted to engage the ear of corn which is to be carried past the cutter 21 and to the husking rolls 22.

Each group of short links preferably comprises a plurality of narrow and wide links which alternate with each other, each narrow link having two longitudinal side plates 50 29, 29, which are spaced close together and each wide link having two side plates 30, 30 which are spaced farther apart and engage on the inner sides of their opposite ends with the outer sides of the plates of adjacent narrow links. The corresponding ends of the plates of each narrow link are spaced apart by means of a roller or sleeve 31 and arranged within this roller is a bushing or tube 32 which extends through openings in 55 the adjacent parts of the plates of the narrow link and engages with the inner sides of the side plates of the respective wide link, and through each of these bushings and the ends of the plates of the adjacent wide link 60 a pivot pin 33 is extended and riveted

against the outer sides of these plates of the wide link, as clearly shown in Figs. 3 and 5 and operating to pivotally connect these links in the usual and well known manner.

The length of each short link is equal to 70 the distance between two adjacent notches or teeth of one of the sprocket wheels on the pitched diameter of the same, so that these links will properly mesh with the sprocket wheels. 75

Each of the long links and the carrying wing associated therewith is preferably constructed as follows:

41 represents two side plates, each of which has its inner part constructed to form 80 a side plate 34 of a long link and also one of the side plates or cheeks 35 of the respective carrying wing. The companion side plates of one of the long links are arranged on the outer sides of the two adjacent narrow links and connected therewith in the same manner in which the side plates of the short wide links are connected with the side plate of the short narrow links, as shown in Figs. 3 and 5. Between the outer parts of 90 the cheeks of the long links is arranged a cross piece 36 which is preferably secured thereto by rivets 37 passing transversely through these parts and upset against the outer sides of the cheeks, as shown in Figs. 95 4 and 5. The front side 38 of this cross piece preferably forms the bearing face of this carrying wing and the same is preferably arranged in line or nearly so with the pivotal connection between the front end of 100 the respective long link and the rear end of the preceding short link, as shown in Fig. 3. By this means any pressure which is exerted against the front side or face of a carrying wing, such as the resistance offered by an ear 105 of corn which is being propelled by the conveyer, will not appreciably tip the carrying wing backwardly, which otherwise would be possible if the face of the carrying wing were arranged a considerable distance in 110 rear of the pivotal connection between its link and the next preceding link owing to the leverage which the carrying wing would otherwise be able to exert on these links. It, therefore, follows that the carrying wing 115 will be always maintained in such a position in which its carrying face is arranged at right angles to the direction of travel of the chain belt, whereby the wing will effectively engage the ear of corn or other article by 120 being carried and ensure proper presentation of the same to the cutter mechanism or husking rolls, or other manner of disposition of the same without liability of the ear of corn or other article, slipping backwardly 125 and escaping over the top of the wing, which otherwise would be possible if the wing were permitted to tilt backwardly and present an inclined bearing surface to the article being propelled.

- The long links formed by the inner parts of the special side plates are so constructed that they span more than one tooth or space of the corresponding sprocket wheel on the 5 pitch line of the same and in the preferred construction the length of the long link from center to center of its pivotal connections with adjacent short links, is such that it is slightly less than twice the distance from 10 center to center of two adjacent teeth of one of the sprocket wheels on the pitch line of the same, this being necessary in order to ensure proper engagement of the opposite ends of the long link of the carrier or wing 15 with the adjacent pair of sprocket teeth, inasmuch as the cord extending from one tooth of the sprocket wheel to the next adjacent tooth is slightly more than half the length of the cord extending from one tooth 20 to the second following tooth of the sprocket wheel.

In the preferred construction the front part of each cross piece of a carrying wing is provided with laterally projecting up- 25 right flanges 39, 39 which engage with the front edges of the cheeks of the wing side plates, thereby not only providing an increased area or bearing surface for engaging with the article to be propelled, but also 30 transmitting the pressure against this cross piece directly to the cheeks and relieving the rivets 37 which connect the same with the cheeks of any undue strain.

In a conveyer thus constructed, it is possible 35 to use standard short links which are comparatively narrow and obtainable at comparatively low cost from manufacturers who make a specialty of this work, thus necessitating manufacturing, specially, only 40 the long links which carry the propelling wings. A considerable saving in cost and in weight of material is thus effected, inasmuch as the greater part of the chain belts is made up of the short standard links and a 45 relatively small part of the length of the chain belts enters into the make up of that part of the same which constitutes the wing portion of the same. Inasmuch as the cost of chain belting of this type increases materially 50 in proportion to the width of the same and it is only necessary to use a comparatively narrow link in the belts of this propeller, it necessarily follows that a considerable saving in cost is effected by making the

major portion of the chain belts of narrow 55 links instead of wide links and only making those links special which require increased length for supporting the carrying wings in such a position that they will not tilt backwardly under the pressure against the ears 60 of corn or other articles and thus preventing the latter from escaping or becoming misplaced.

I claim as my invention:

1. A conveyer section having two side 65 plates, the inner parts of which form the side plates of a link which are adapted to be pivotally connected at their front and rear ends with other links and each of which is provided with a laterally extending cheek 70 forming part of a wing, and a cross piece arranged between said cheeks and provided on its front side with a bearing face.

2. A conveyer section having two side 75 plates the inner parts of which form the side plates of a link which are adapted to be pivotally connected at their front and rear ends with other links and each of which is provided with a laterally extending cheek 80 forming part of a wing, a cross piece arranged between said cheeks and provided on its front side with a bearing face, and fastenings passing through said cheeks and cross piece.

3. A conveyer section having two side 85 plates, the inner parts of which form the side plates of a link which are adapted to be pivotally connected at their front and rear ends with other links and each of which is provided with a laterally extending cheek 90 forming part of a wing, a cross piece arranged between said cheeks and provided on its front side with a bearing face, and with flanges arranged in front of said cheeks. 95

4. A conveyer section having two side plates, the inner parts of which form the side plates of a link which are adapted to be pivotally connected at their front and rear ends with other links and each of which 100 is provided with a laterally extending cheek forming part of a wing, and a cross piece arranged between said cheeks and provided on its front side with a bearing face and with flanges arranged in front of said 105 cheeks, and fastenings passing through said cross piece and cheeks.

CLARENCE A. HOY.
